KING M. RANDOLPH, OF KNOXVILLE, TENNESSEE, ASSIGNOR OF FORTY ONE-HUNDREDTHS TO CARY F. SPENCE, OF KNOXVILLE, TENNESSEE

GARMENT BAG

Application filed October 14, 1931. Serial No. 568,808.

This invention relates to improvements in garment bags, and in general, aims to facilitate the process of placing a garment in the paper bags commonly used in laundries and 5 cleaning establishments by providing a bag which is so constructed and supported that it drops into the garment-covering position.

In the accompanying drawing of a preferred embodiment of the invention,—

10 Fig. 1 is an elevation of the improved bag, a part of which is shown broken away to disclose the manner in which the string is initially attached to it;

15 Fig. 2 is an elevation showing the way in which the bag drops into garment-covering position; and

Fig. 3 is a section on line 3—3 of Fig. 1.

The placing of a garment in a paper or similar bag is quite a laborious and tedious 20 process because of the ease with which garments, freshly laundered or pressed, may be wrinkled if wrongly inserted in such bags, also because of the certainty of tearing the bags if the step is accomplished hurriedly. 25 In accordance with the invention, I provide a novel bag which when in use effects the placing of a garment inside the bag expeditiously, saving time and labor and obviating tearing of the bags.

30 Referring particularly to the drawing, there is shown in Fig. 1 a bag 5, of paper or other material, which is properly shaped to enclose the particular kind of garments with which it is to be used. The precise manner 35 in which the body of this bag is put together does not enter into this invention; the only essentials being that the bag have an open bottom, as shown, and a top with an aperture in it several inches long. A string 6, preferably knotted so as to be endless, is secured within the bag at point 7, as by paste, glue or by mechanical fastening means, the essential feature being that the fastening means 40 must give way when the weight of a garment is placed on the lower end of the string, which, as shown, projects from the open bottom of the bag. It is also desirable that the string be long enough to extend out through the aperture at the top of the bag, as 45 shown, and that the attachment of the string

to the bag be such that the bag is not torn when its connection with the string gives way. While connection 7 is shown as a loop, obviously it may have many forms, the essential point being to provide a surplus length 55 of string at the connection, so that a weight on the lower end of the string breaks said connection before the mass of the weight is sustained by the string.

When the bag is to be placed over a garment, as in a laundry or cleaning establishment just before the delivery wagon leaves the shop, the bag is placed under an elevated support, such as a pole 8, which may be suspended from the ceiling or attached to a wall 60 of the room. This permits the lower end of string 6 to dangle below the end of the bag. The operator now simply hangs the garment 65 9, preferably previously placed on a garment hanger 10, upon the lower end of string 6. 70 Immediately connection 7 gives way, and the string straightens out, as shown in Fig. 2. The bag is then unsupported, and moves by gravity down the string until it surrounds the garment, as indicated in dotted lines 75 in Fig. 2. The garment, fully enclosed by the bag, may be removed by simply unhooking hanger 10 from the string, and may then be placed in the delivery wagon or wherever 80 desired.

The present invention effects an important improvement in present methods of protecting clothes by means of bags, as about $\frac{1}{10}$ of the time now spent in fussing with bags 85 is saved, or in other words, an operator can place about ten garments in ten bags in the time now spent inserting a single garment by hand in a bag.

Obviously, the present invention is not restricted to the particular embodiment thereof herein shown and described.

What I claim is:—

1. A garment bag comprising, in combination, a bag having an open bottom and a top which is partly open; and a string secured inside the bag intermediate its ends so that its connection will give way as soon as any substantial weight is put on the string, without tearing the bag; said string being longer 95 100

than the bag, and its connection comprising a loop.

2. A garment bag comprising, in combination, a bag having an open bottom and a top which is open at the middle but otherwise closed; and a string secured for a portion of its length, intermediate its ends, to the bag on the inside by paste or glue, said string being endless and long enough to extend out the top of the bag and below the bottom of the bag, and having the secured portion of its length arranged in a shape other than a straight line.

3. A garment bag having openings at its top and bottom; and a string secured intermediate its ends within the bag by fastening means which will readily give way when a weight is placed on the lower end of the string with the upper end of the string supported; the string adjacent the points where it is secured to the bag, providing a surplus length of string permitting the weight to break away the fastening means before the entire length of the string sustains the load of the weight.

In testimony that I claim the foregoing as my own, I have hereto affixed my signature.

KING M. RANDOLPH.
